UNITED STATES PATENT OFFICE.

EUGENE W. HAWLEY, OF MILWAUKEE, AND GEORGE H. WHEARY, OF RACINE, WISCONSIN,
ASSIGNORS TO THE HARTMAN TRUNK COMPANY, OF RACINE, WISCONSIN.

GARMENT-HANGER.

No. 902,078.

Specification of Letters Patent.

Patented Oct. 27, 1908.

Application filed May 18, 1908. Serial No. 433,462.

To all whom it may concern:

Be it known that we, EUGENE W. HAWLEY and George H. Wheary, both citizens of the United States, and residents, respectively, of Milwaukee, in the county of Milwaukee, and of Racine, in the county of Racine, State of Wisconsin, have invented certain new and useful Improvements in Garment-Hangers; and we do hereby declare that the following 10 is a full, clear, and exact description thereof.

Our invention consists in what is herein particularly set forth with reference to the accompanying drawings and pointed out in claims herewith, its object being to provide 15 simple, economical and efficient yielding garment-hangers especially designed for wardrobe-trunks to compensate for the jars to which such trunks are subjected in travel, whereby fracture of stiff hanger-bars, 20 straightening out of the hanger-hooks or bending of the rods from which the hangers are suspended is avoided.

Figure 1 of the drawings represents a partly sectional side elevation of a yielding bar garment-hanger in accordance with our 25 invention; Fig. 2, a similar view of a similar hanger having a spring auxiliary to the one shown in Fig. 1, and Fig. 3, a like view of a fragment of another form of our garment- 30 hanger having a spring-controlled stiff-bar guided on the shank of the hanger-hook.

Referring by letter to the drawings, A indicates the hook and B the stiff bar of one of our improved garment-hangers, an upper 35 shoulder *b* being provided on the shank of the hook that extends vertically through an eye in said bar central of same, this bar being preferably of wood.

In Figs. 1 and 2, the lower end of the 40 hook-shank is shown rigidly secured to a support in the form of a semi-elliptical spring C midway between the ends of same, these loose ends of the spring being provided with ears e that lap opposite sides of 45 the bar B to prevent displacement of the spring and to guide the same in its expansion and contraction longitudinally of said bar. As shown in Fig. 2, the semi-elliptical spring C may be supplemented by a spiral spring 50 D confined on the shank of the hook A between said semi-elliptical spring and a washer d on said hook-shank in opposition to the bar B of the hanger.

In Fig. 3, the semi-elliptical spring is 55 omitted and a spiral-spring D' is shown

seated upon a support in the form of a cup e on the lower end of the shank of the hook A, its upper end being opposed to a washer d' abutting the under surface of the hanger- 60 bar.

In any form of our invention, there is spring-resistance to weight on the stiff hanger-bar, the spring or springs under tension below said bar, being sufficiently strong to support the load under ordinary circumstances, but in case of sudden downward movement of said load, there is yield of said spring or springs to compensate for the strain that would otherwise have a tendency to fracture the aforesaid hanger-bar, 70 straighten out the hanger-hook or bend the suspension-rod with which the hook is engaged, and while we have shown preferred forms of our invention, the latter is generic to any garment-hanger having a spring-controlled stiff bar guided on the shank of a suspension device below a shoulder of same against which it is normally impinged under tension of its controlling spring, whereby said bar is movable with a load thereon incidental to sudden downward displacement of said load. 75 80

We claim:

1. A garment-hanger comprising a suspension device having a shouldered shank, a 85 stiff bar guided on the shank below the shoulder of same, a support in connection with the lower end of said shank, and a spiral-spring surrounding the aforesaid shank under tension between the bar and 90 support the expansive force of the spring being exertive against said bar to normally hold the same against the shank-shoulder.

2. A garment-hanger comprising a suspension device having a shouldered shank, a 95 stiff-bar having a central eye engaged by the shank below the shoulder of same, a support in connection with the lower end of said shank, and a spiral-spring surrounding the aforesaid shank under tension between the bar and 100 support, the expansive force of the spring being exertive against said bar to normally hold the same against the shank-shoulder.

3. A garment-hanger comprising a hook, 105 a stiff-bar guided on the shank of the hook, and a semi-elliptic spring in connection with the hook-shank under said bar against which it is loose at its ends to be expansile and contractile longitudinally of the same. 110

4. A garment-hanger comprising a hook, a stiff bar guided on the shank of the hook, a semi-elliptic spring in connection with the hook-shank under said bar, and a spiral-
5 spring surrounding said hook-shank intermediate of the aforesaid bar and semi-elliptical spring.

5. A garment-hanger comprising a hook, a stiff-bar guided on the shank of the hook,
10 a semi-elliptic spring in connection with the hook-shank under said bar, and ears at the

ends of the spring lapping opposite sides of said bar.

In testimony that we claim the foregoing we have hereunto set our hands at Racine in 15 the county of Racine and State of Wisconsin in the presence of two witnesses.

EUGENE W. HAWLEY.
GEO. H. WHEARY.
